[57] CLAIM

The ornamental design for a hunter's vest, as shown and described.

DESCRIPTION

FIG. 1 is an outside elevational view of a hunters vest in an open condition, showing our new design, the broken lines shown throughout the views being understood to represent conventional stitching;

FIG. 2 is an outside elevational view thereof;

FIG. 3 is a front elevational view thereof in the condition of use; and,

FIG. 4 is a rear elevational view of FIG. 3.

Fig. 2.

Fig. 4.

Fig. 3.
